UNITED STATES PATENT OFFICE.

WILLIAM E. HUTCHINGS, OF LOUISVILLE, KENTUCKY.

HOIST FOR UNLOADING SHIPS.

SPECIFICATION forming part of Letters Patent No. 700,051, dated May 13, 1902.

Application filed September 12, 1901. Serial No. 75,142. (No model.)

To all whom it may concern:

Be it known that I, WILLIAM E. HUTCHINGS, a citizen of the United States, residing at Louisville, in the county of Jefferson and State 5 of Kentucky, have invented a new and useful Improvement in Hoists for Unloading Ships, of which the following is a specification.

My invention relates to a contrivance for unloading ships placed and contained entirely on the ship to be unloaded, as distinguished from various apparatus now in general use for the same purpose which are placed and contained entirely on the dock to which the ship is to be unloaded.

15 My contrivance is devised solely for unloading coal, ore, and like bulky but separable material.

I attain the desired results by the mechanism illustrated in the accompanying drawings, in which—

Figure 1 is a side elevation of the contrivance, together with a cross-section of the ship through one of its hatches and a part of the dock to which the ship is to be unloaded. 25 Fig. 2 is a plan of a portion of the ship's deck and a portion of the dock and shows the relative position of the apparatus and the ship's hatches. Fig. 3 is a cross-section taken through the trolley-wagon and trolley-track. 30 Similar letters refer to similar parts in all the figures.

A is a boom or trolley-track, of "I-beam," "channel," or "built-up" design, fastened to the deck of the ship D by means of the hinge 35 E in the pivoted shoe B. The boom or trolley-track A extends from the deck-shoe B in an inclined direction upward across the ship's hatch F and over the dock C and is held in position by the guy-lines G passing through 40 sheaves attached to the masts H. Said masts are partly supported by the stays or rigging X X. By adjustment of the guy-lines G and by virtue of the hinge and pivot in the deck-shoe B the boom or trolley-track A may be 45 raised or lowered vertically or swung laterally.

Upon the boom or trolley-track A a trolley-wagon J J' travels, rolling on its wheels K, and limited in its travels by the two stops L and L'. At the stop L' the wagon is represented by dotted lines. I prefer to make said 50 boom or trolley-track a single beam of I-beam section and to arrange the trolley-wagon so

that it runs on and astride of the bottom flange thereof. From the trolley-wagon J the bucket or shovel M of the "automatic" or 55 self-loading and self-dumping type is suspended in the following manner:

There are two lines N; but the lower end of only one can be shown, the other being necessarily directly behind it on this elevation. One of these lines N is attached to the trolley-wagon J at O, passes around a pulley on the bucket M, thence up over a sheave P on the trolley-wagon, thence over a sheave at the outer end Q of the trolley-track, thence 60 over a sheave R near the inner end of the boom, thence over a sheave S, attached to the ship's deck, over a sheave T, attached to the deck, to the drum U of the hoisting-engine V. The other line N is attached to the bucket M 65 at O', thence runs through a series of sheaves on said bucket designed for opening and closing same by a system heretofore invented and patented, thence over a sheave P on trolley-wagon J, and thence follows a course parallel to the other line over concentric sheaves 70 until they pass sheave S, after which they separate, as shown on Fig. 2; this line passing through sheave T' and thence to drum U. This line may also, if desired, be attached to 75 the trolley-wagon and run thence through a system of sheaves on the bucket.

In operation the bucket M is closed upon the material in the hold W of the ship by hauling on one of the lines N and is then hoisted by 80 both lines N until in the position M' it comes in contact with the trolley-wagon J, when a continuation of the pull on both lines N causes the trolley-wagon, with the bucket, to travel up the boom or trolley-track to the position 85 J' M', being prevented from going farther by the stop L. One line N is then slackened off, allowing the bucket to open and deliver its contents onto the dock C below. Both lines N are then slackened off, allowing the trolley-wagon, with bucket, to return by gravity along the boom or trolley-track A to its original position J, being stopped by stop L. A further slackening of both lines N permits the bucket 90 to descend again into the hold W of the ship, 95 in readiness to repeat the above-described operations.

To further facilitate the operation of the trolley-wagon J on the boom or trolley-track

A, a third line may be attached to said trolley-wagon and lead over sheaves similar to R, S, and T to a third drum on the hoisting-engine. The object of this line is to assist gravity in bringing the trolley-wagon back to its original position. The boom or trolley-track A is also arranged so as to be detached from its fastenings and lowered to the deck when so desired.

10 I do not claim as my invention the bucket M, the trolley-wagon J, the boom or trolley-track A, or the hoisting-engine V, all of which are known by me to have been in use for some time in various modified forms and combinations for handling of material; but

15 What I do claim as my invention, and desire to secure by Letters Patent, is—

1. In hoists for unloading ships, the combination of a trolley-wagon J, an inclined trolley-track A attached to the deck of the ship by a hinge and pivot, and supported from above by guys; said trolley-track being a single beam of "I-beam" section, with the wheels of the trolley-wagon running on and astride 20 of the bottom flange thereof, together with lines N attached to a bucket M, running

through said trolley-wagon and along said trolley-track; said lines being controlled by engines, all for the purpose of lifting freight out of the ship's hold toward the outward end 30 of the trolley-track, in order to transfer it to a dock or to another ship, substantially as described.

2. In hoists for unloading ships, the combination of a trolley-wagon J an inclined trolley-track A attached to the deck of a ship by a hinge and pivot, and supported from above by guys, together with lines N attached to a bucket M, running through said trolley-wagon and along said trolley-track; said lines to be 35 controlled by engines, all for the purpose of lifting freight out of the ship's hold toward the outward end of the trolley-track, in order to transfer it to a dock or to another ship, substantially as described. 40

45 Signed at Louisville, Kentucky, September 9, 1901.

WILLIAM E. HUTCHINGS.
